(57) **CLAIM**

The ornamental design of a ventilator, as shown and described.

DESCRIPTION

FIG. 1 is a front perspective view of a ventilator according to our new ornamental design;
FIG. 2 is a front view thereof;
FIG. 3 is a rear view thereof;
FIG. 4 is a top view thereof;
FIG. 5 is a bottom view thereof;
FIG. 6 is a left side view thereof;
FIG. 7 is a right side view thereof; and,
FIG. 8 is a rear perspective view thereof.
The broken lines represent surrounding structure and do not form part of the claimed design.
